DESIGN FOR A HALTER OR SIMILAR ARTICLE

Dorothea Doctors, New York, N. Y., assignor, by mesne assignments, to Dorothea Doctors and Sidney A. Fox, both of New York, N. Y., copartners, trading under the firm name and style of "Dorothea Doctors"

Application February 26, 1936, Serial No. 61,360

Term of patent 14 years

To all whom it may concern:

Be it known that I, Dorothea Doctors, a citizen of the United States, residing in the county, city, and State of New York, have invented a new,
original, and ornamental Design for a Halter or Similar Article, of which the following is a specification, reference being made to the accompanying drawing, forming a part thereof.

Fig. 1 is a front view of a halter or similar article as it appears on the wearer.

Fig. 2 is a front view of the same in
"straightened-out" position.

The essential feature of this invention resides
in breast receiving pockets which are stitched,
as shown.

I claim:

The ornamental design for a halter or similar article substantially as shown and described.

DOROTHEA DOCTORS.
